UNITED STATES PATENT OFFICE

LOUIS BLUMENTHAL, OF BROOKLYN, NEW YORK

FOLDING TABLE AND CHAIR

Application filed July 29, 1932. Serial No. 625,595.

My invention relates to folding furniture of the type which is adapted to be folded into a compact bundle for ease in transportation and storage.

5 The object of my invention is to provide an article of the class described comprising a table and two chairs or benches of such a construction that when not in use the table and chairs are entirely enclosed in a compact 10 bundle which requires a minimum amount of space for storage.

A further object of my invention is the provision of a device of the character described comprising in a single structure two tables, 15 or rather one extensible table, and four chairs or benches.

The development of folding furniture has been very rapid in the last decade or two. The trend of development, however, has, apparently, been toward more complicated devices having a great number of adjustable parts which become defective in operation after a short time. The employment of a 20 large number of adjustable parts in folding 25 furniture has the further disadvantage that, as a general rule, the stability and strength of the furniture decreases as the number of adjustable parts increases.

It is therefore an additional object of my 30 invention to provide devices of the character defined above which will have a minimum number of adjustable parts and the adjustable parts of which will be of the simplest character. The devices, according to my invention therefore, have the advantage of being strong, comparatively indestructible and 35 easily operated.

Further objects and advantages of my invention will appear from the detailed description of the accompanying drawings in which,

Fig. 1 is a perspective view of a single table and chairs or benches in operative position;

Fig. 2 is a detail of one of the benches in perspective showing the hinged construction of the supporting leg;

Fig. 3 is a perspective of the table and one of the benches in folded position;

Fig. 4 is a perspective of the complete device in folded position; and

Fig. 5 is a perspective of a modification of the device shown in Fig. 1 having two tables and four benches.

Referring to the drawings in detail, 1 represents a back or supporting member having a ledge 2 at its upper end. Hinged to the outer edge of the ledge 2 in such a manner as to fold downwardly on the supporting member is a table 3 which is supported by a bracket 4 (shown in dotted lines in Fig. 1) hinged to the supporting member 1 in such a fashion as to fit under the ledge 2 when in folded position. Hinged to either side of the supporting member 1 is a bench, comprising a back 5, a seat 6 hinged to the back 5 and a supporting leg for the seat comprising a member 7 hinged to the bottom of the seat, and a member 8 hinged at one end on its under face to the member 7 and at the other end on its upper face to the back of the bench 5. The purpose of the member 8 is to keep the member 7 in an upright position when the seat is open. These members are so arranged that when the seat is closed, the member 8, being of the same thickness as the seat 6, is coextensive therewith with the member 7 superimposed upon both of them. This construction reduces the thickness of the bench when in closed position to the thickness of the seat, plus the thickness of the back, plus the thickness of the member 7.

Each bench has a winged portion 9 which carries at its free edge the hinges by which the benches are hinged to the supporting member 1. Each wing member 9 has a width equal to the thickness of the table, plus the thickness of bracket 4, plus the thickness of the bench seat, plus the thickness of the bench back. Accordingly, the thickness of the bundle, when the device is in folded position, is simply the thickness of the member 9, plus the thickness of the supporting member 1.

The back of one of the benches 5 carries at its free end a hook 10, and the back of the other bench carries at its free end a stud or eye 11 which is adapted to be engaged by the hook 10 to hold the device in folded position. It is obvious that any other conven-

tional fastening device may be used in place of the elements 10 and 11.

As is apparent from Figs. 3 and 4, the width of the ledge 2 is just sufficient to permit the supporting bracket 4 to rest between the table 3 and the supporting member 1 when the table is in vertical folded position. This construction eliminates the loss of any space, and, at the same time, makes it possible for the top of the bracket 4 to be made absolutely flush with the bottom of the ledge 2, and the bottom of the table 3, thereby eliminating any wobbling of the table top when it is in open position.

15 Likewise, as is shown in Fig. 4, the supporting legs of the seats 6 are so arranged with regard to the width of the table that, when the benches are folded over on the table, the legs of the benches assume a position adjacent the edge of the table whereby the seats 6 of the benches are closely superimposed upon the table top. Here again, the arrangement of parts is such as to absolutely avoid any waste of space.

25 Fig. 5 illustrates the manner in which my device may be modified to provide double the seating room and table space normally provided thereby. Similar parts in Fig. 5 will be designated by the numerals applying to 30 these parts in Figs. 1 to 4.

The device illustrated in Fig. 5 differs from that shown in Figs. 1 to 4, merely by the fact that the ledge 2 is twice as wide as it is in the device of Figs. 1 to 4 and instead of stopping at the two ends of supporting member 1 continues to the base of supporting member 1. The wings 9 of the benches or chairs, accordingly, instead of being hinged on the supporting member 1 are hinged on 40 the respective edges of the ledge 2. The purpose of the extension of ledge 2 to the base of the supporting member 1 is to provide space for the abutment of adjacent wing members 9 when adjacent benches are in open 45 position. Since the other constructional features of the device shown in Fig. 5 are the same as those shown in Figs. 1 to 4, a further discussion thereof can be dispensed with.

50 My device can be constructed of any suitable material, preferably a light wood to facilitate transportation. It is peculiarly adapted for use in a great number of instances where space must be economized. It is particularly suitable for use as a breakfast nook in small kitchens in which an ordinary table and chairs or benches would be in the way of a person working. When in folded position it can be readily secured to an automobile or other vehicle for transportation to a suitable stopping place for a picnic. It forms a very desirable item in the equipment of tourists who camp along their itinerary.

65 My device can be made any desired size

and the table and chairs can be made in any preferred design without departing from the scope of my invention.

It is to be understood also that where hinges are shown in the drawing, they can be replaced by any other conventional means for swingably attaching one element to another, such as pivots.

Having thus described the nature and objects of my invention and illustrated preferred embodiments of the same, which embodiments are to be taken as illustrative rather than limitative, what I claim as new and desire to secure by Letters Patent is:

1. In a device of the character described, in combination, a normally upright supporting member, a table swingably connected to the top of said supporting member, a seat assembly and means for swingably connecting said seat assembly to a side edge of said supporting member whereby said seat assembly may be folded in spaced relation to said supporting member.

2. In a device of the character described, in combination, a normally upright supporting member, a ledge projecting from the upper edge of said supporting member, a table swingably connected at one of its edges to the free edge of said ledge, a bracket swingably mounted on said supporting member and adapted, when swung perpendicular to said supporting member, to support said table in open position, a seat assembly and means for swingably connecting said seat assembly to a side edge of said supporting member whereby said seat assembly may be folded in spaced relation to said supporting member.

3. In a device of the character described, in combination, a normally upright supporting member, a ledge projecting from the upper edge of said supporting member, a table swingably connected along one of its edges to the free edge of said ledge, a bracket swingably connected to said supporting member and adapted, when swung perpendicular to said supporting member, to support said table in open position, a wing member swingably connected along one of its edges to each end of said supporting member, and a seat assembly secured perpendicular to the face of said wing member along its edge opposite the edge connected to said supporting member.

4. In a device of the character described, in combination, a normally upright supporting member, a ledge projecting from the upper edge of said supporting member, a table swingably connected along one of its edges to the free edge of said ledge, a bracket swingably connected to said supporting member and adapted, when swung perpendicular to said supporting member, to support said table in open position, a wing member swingably connected along one of its edges to each

end of said supporting member, and a seat assembly secured perpendicular to the face of said wing member along its edge opposite the edge connected to said supporting member, each wing member having a width at least equal to the thickness of the seat assembly, plus the thickness of the table, plus the thickness of the bracket.

5. In a device of the character described, 10 in combination, a normally upright supporting member, a ledge projecting from the upper edge of said supporting member, a table swingably connected along one of its edges to the free edge of said ledge, a bracket 15 swingably connected with said supporting member and adapted, when swung perpendicular to said supporting member, to support said table in open position, a wing member swingably connected along one of its 20 edges to each end of said supporting member, a seat back secured perpendicular to the face of said wing member along its edge opposite the edge connected to said supporting member, a seat swingably connected to 25 said seat back, and a supporting leg for said seat comprising a normally upright member swingably connected to the under surface of said seat and a connecting link having one of its ends swingably connected to said normally upright member and its other end swingably connected to said seat back.

6. In a device of the character described, 30 in combination, a normally upright supporting member, a ledge projecting from the upper edge of said supporting member, a table swingably connected along one of its edges to the free edge of said ledge, a bracket swingably connected with said supporting member and adapted, when swung perpendicular 35 to said supporting member, to support said table in open position, a wing member swingably connected along one of its edges to each end of said supporting member, a seat back secured perpendicular to the face of said wing 40 member along its edge opposite the edge connected to said supporting member, a seat swingably connected to said seat back, and a supporting leg for said seat comprising a normally upright member swingably connected to the under surface of said seat, at a point spaced 45 from the end of said normally upright supporting member, a distance less than the distance between the end of said normally upright supporting member and the adjacent end of the table, and a connecting link having one of its ends swingably connected to said normally upright member and its other end swingably connected to said seat back, each of said wing members having a width equal to the thickness of the seat in folded position, plus the thickness of the table, plus the thickness of the bracket.

7. In a device of the character described, 50 in combination, a normally upright supporting member, a ledge projecting from the upper edge of said supporting member, a table swingably connected along one of its edges to the free edge of said ledge, a bracket swingably connected with said supporting member 55 and adapted, when swung perpendicular to

said supporting member, to support said table in open position, a wing member swingably connected along one of its edges to each end of said supporting member, a seat back secured perpendicular to the face of said wing member along its edge opposite the edge connected to said supporting member, a seat swingably connected to said seat back, and a supporting leg for said seat comprising a normally upright member swingably connected to the under surface of said seat, at a point spaced from the end of said normally upright supporting member, a distance less than the distance between the end of said normally upright supporting member and the adjacent end of the table, and a connecting link having one of its ends swingably connected to said normally upright member and its other end swingably connected to said seat back.

8. In a device of the character described, 80 in combination, a normally upright supporting member, a ledge projecting from the upper edge of said supporting member, a table swingably connected along one of its edges to the free edge of said ledge, a bracket swingably connected with said supporting member and adapted, when swung perpendicular to said supporting member, to support said table in open position, a wing member swingably connected 85 along one of its edges to each end of said supporting member, a seat back secured perpendicular to the face of said wing member along its edge opposite the edge connected to said supporting member, a seat swingably connected to said seat back, and a supporting leg for said seat comprising a normally upright member swingably connected to the under surface of said seat, at a point spaced 90 from the end of said normally upright supporting member, a distance less than the distance between the end of said normally upright supporting member and the adjacent end of the table, and a connecting link having one of its ends swingably connected to said normally upright member and its other end swingably connected to said seat back, each of said wing members having a width equal to the thickness of the seat in folded position, plus the thickness of the table, plus the thickness of the bracket.

In testimony whereof I have hereunto set my hand.

LOUIS BLUMENTHAL.
